To all whom it may concern:

Be it known that I, Earl S. Jacobsen, a citizen of the United States and resident of Shelton, in the county of Fairfield and State of Connecticut, have invented a new, original, and ornamental Design for a Pile Fabric, of which the following is a specification, reference being had to the accompanying drawing, forming a part thereof.

The figure is a plan view of a pile fabric show-

I claim:

The ornamental design for a pile fabric substantially as shown and described.
